WITNESS:

UNITED STATES PATENT OFFICE.

HANS B. NESSLER, OF CHICAGO, ILLINOIS.

CLAMP.

Application filed January 20, 1923. Serial No. 613,990.

To all whom it may concern:

Be it known that I, HANS B. NESSLER, a citizen of the United States, residing at Chicago, in the county of Cook and State of Illinois, have invented new and useful Improvements in Clamps, of which the following is a specification.

This invention relates to a clamp, the general object of the invention being to provide a device for clamping a piece of silk over a type form when printing imitation typewritten letters.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a plan view of a form showing the invention in use.

Figure 2 is a section on line 2—2 of Figure 1.

Figure 3 is an enlarged view of one of the clamps.

Figure 4 is a horizontal section of one of the clamps.

Figure 5 is a detail view.

In these views 1 indicates a pair of clamps which are placed one at each end of the type form so that they will engage the ends of the silk strip 2 which is placed over the form in printing imitation typewritten let-

ters. Each clamp consists of a box 3 having its top open and one side of which is provided with holes 4. A bar 5 is located in the box and this bar is provided with recesses 6 in one side for receiving the extensions 7 of the turning screws 8, these screws engaging the screw threaded holes 4. The heads 9 of the screws are provided with sockets 10 for receiving a pin wrench so that the screws can be rotated. A strip of wood 11 is inserted in the box and this strip is to have the end of the silk strip placed around the same, as shown at 12, and then the screws are tightened to clamp the wooden strip between one side of the box and the clamping bar 5.

From the foregoing description it will be seen that the ends of the silk strip are securely held in the boxes. The silk can be attached after the form is locked up and can be changed or removed without removing or unlocking the form.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A device of the class described comprising a box, a clamping bar located therein, screws engaging holes in the box and recesses in the bar for receiving the screws and a wooden strip engaged by the clamping bar.

In testimony whereof I affix my signature.

HANS B. NESSLER.
